11 Claims. (Cl. 242—18)

The invention relates to a precision yarn winding machine. An example of a precision yarn winding machine is shown on page 348 Fig. 2 of the second edition of the American Cotton Handbook. In this type of machine there is a driven spindle which carries the yarn package whilst the yarn is guided by a device which moves to and fro along the outer surface of the yarn package in such a way that a cross wind package is produced. In the usual forms of the precision winder the device which moves the yarn to and fro, the so-called yarn guide, is mounted at the end of a rod, the traverse bar, which slides to and fro in a slot or the like in the swinging traverse frame. This traverse frame must be capable of moving in order to make it possible for the yarn guide to continue to execute its movement in the immediate vicinity of the outer surface of the yarn package as the diameter of this yarn package grows. In the usual precision winding machines, the traverse frame is for this purpose capable of swinging around a shaft which is parallel, or practically parallel, to the spindle. This shaft is driven together with the spindle and is capable of rotating in bearings in the frame of the machine as well as in the traverse frame, without causing rotation of the traverse frame. This shaft carries a device, usually called a "traverse-cam," but which in fact is a body possessing a slot situated on a cylindrical surface, this surface being concentrical with the shaft. A projection of the traverse rod is situated in the slot of the traverse cam, whilst the slot is shaped in such a way that the rotating traverse cam causes this projection, the traverse rod and the yarn guide to move to and fro in the desired way in the traverse frame. The type of winding is determined by a suitable choice of the relation between the rotational speed of the spindle and the rotational speed of the shaft carrying the traverse cam. In some winding machines the position of the traverse frame is determined by the fact that the smooth and more or less spherical part of the yarn guide rests against the outer surface of the yarn package. In other winding machines, suitable for winding yarns which cannot stand friction, the traverse frame possesses a freely rotatable roller, the so-called roller bail, by means of which this traverse frame rests against the yarn package.

The invention relates to a new construction of such a precision winding machine. According to the invention the relative movement of the spindle carrying the yarn package and the frame in which the device determining the spot where the yarn is wound on the yarn package moves to and fro, this relative movement being necessary in order to allow for the growing diameter of this yarn package, is a rectilinear translational motion.

The invention embodies various advantages, which will be discussed below.

It is desirable, that the traverse frame should exert not more than a slight pressure on the yarn package, this pressure being either constant or varying according to a pre-determined function of the yarn package diameter. For this purpose, in the usual machines the traverse frame

2

must be perfectly balanced, and must moreover be provided with means to cause the desired pressure to be established. When on a usual winding machine, a conical yarn package is to be wound, and the traverse frame is provided with a pressure roll by means of which it rests against the yarn package, then the entire length of this roll will rest against a generatrix of the conical yarn package in one position of the traverse frame only. In all other positions of the traverse frame the pressure roll will rest against the yarn package, in theory only in one point, and in practice with only a small part of its length. The result of this is that the density of the package is not the same throughout this package. If the traverse frame is not provided with a pressure roll, the yarn guide will move along a generatrix of the yarn package in one position of the traverse frame only; in all other positions of this traverse frame the yarn guide describes trajectories which deviate from a generatrix, thus causing the pressure exerted by the yarn guide on the yarn package to vary; this is equally undesirable from the point of view of the formation of a package of constant density. It is desirable for the density of the package to be constant throughout as inconstant density causes difficulties in uniform dyeing in the case of package yarn dyeing, whilst, moreover, the forces necessary for unwinding the yarn package over the end will not be constant, this causing trouble, especially in knitting machines. Further, the usual precision winders have the disadvantage that the forces exerted by the traverse cam on the traverse rod possess components, the directions of which are such, that they result in torques exerted on the traverse frame around the shaft of the traverse cam, these torques tending to move the traverse frame either towards the yarn package or away from this package. The said forces vary during each complete revolution of the traverse cam and thus cause varying forces to be exerted on the yarn package. Although it is true that the forces in the direction of the yarn package are to a certain extent counteracted by a device preventing the movement of the traverse frame towards this package, this device, as a rule, still has a slight backlash, so that it will still permit a slight movement of the traverse frame, resulting in a part of the said forces being exerted on the yarn package. Furthermore, this yarn package must, as its diameter grows, push the traverse frame backwards by means of the pressure roll or the yarn guide, as a result of which the yarn package is subjected to all the forces acting on the traverse frame. These forces reach their maximum value at the moment at which the direction of the motion of the traverse bar reverses, and they will cause variations of the density, in the vicinity of the ends of the package. The disadvantages mentioned are especially important when monofil nylon and such like yarns are to be wound, as in these cases, owing to the thinness and the smoothness of the yarn, the winding machine must satisfy exacting requirements. Moreover, the usual machine needs a so-called pine-apple attachment in order to be able to wind a pine-apple cone. This is a disadvantage, because the pine-apple attachment is a device which is subject to serious wear, and which, with its many small parts and its relatively large back-lash, limits the permissible rotational speed of the machine. When a precision winding machine is executed according to the invention, the balancing of the traverse frame is, as a rule, superfluous, as it is possible to cause this frame to execute its motion in a horizontal plane; the traverse cam cannot exert forces on the traverse frame, as a consequence of which the forces exerted on the yarn package by the traverse frame show less variation; a roller bail, if such a device is present, will continue to rest against a generatrix of the yarn package, independent of the diameter of this package, whilst the trajectory of a yarn guide resting

directly on the yarn package coincides continuously with such a generatrix. Moreover, a winding machine according to the invention is capable of winding yarn package of various forms, especially of winding pine-apple cones, without needing the assistance of devices which show such heavy wear and such large back-lash as the usual pine-apple attachment. An accidental advantage of the machine according to the invention is found in the possibility of mounting, in a simple way, a transmission gear with continuously variable transmission ratio, the transmission ratio of which gear is adjusted, either by the traverse frame whilst moving away from the yarn package, or by the spindle whilst moving away from the traverse frame, this adjustment being such that the yarn speed remains constant, or at any rate varies less in accordance with the diameter of the yarn package than is the case in a winding machine with a constant rotational speed of the spindle. Various embodiments of the invention are illustrated in and hereinafter described with reference to the accompanying drawings.

In the said drawings:

Fig. 1 is a plan view of a precision winding machine according to the invention for the winding of pine-apple cones.

Fig. 1A shows a modified form of a detail of the machine according to Fig. 1.

Fig. 2 shows a detail of the traverse mechanism of the machine according to Fig. 1.

Fig. 2A is an enlarged cross sectional view taken along line 2A—2A of Figure 1.

Fig. 3 shows a precision winding machine for the winding of cones of rounded shape.

Fig. 3A is an enlarged cross sectional view taken along line 3A—3A of Figure 3.

Figs. 4 and 5 show traverse mechanisms of machines operating with constant traverse length.

Figs. 6A and 6B show devices suitable for the purpose of causing the traverse frame to exert the desirable pressure on the yarn package in every position.

The Figures 7 and 8 show precision winding machines according to the invention with variable speeds of the spindles.

Fig. 9 shows a precision winding machine according to the invention for the winding of cones which can be unwound in a simple way from the inside.

Fig. 10 shows a winding machine according to the invention in which the fulcrum of the lever which drives the traverse rod is carried by the traverse frame.

Fig. 11 shows a modification of the traverse bar driving mechanism.

A machine according to the invention for the winding of normal pine-apple cones will now be described with reference to Fig. 1. In this figure 117 is a spindle, which is rotatable in a first frame 124 of the machine, and which carries a holder 116 for a tube on which the yarn package 114 is wound. The spindle is driven in the usual way by means of a belt 125 and a pulley 126. The yarn to be wound passes to the yarn guide 103 through the loop guide, a stub catcher and the tension device, which are not shown in the figure. The yarn guide is mounted at the end of a traverse bar 105, which is capable of sliding in a primary guide means formed by the trackway 130 of a traverse frame 101. This second frame can be shifted by the yarn package building up, for which purpose bearing 110 which is fixed to the traverse frame slides over a bar 111, and the bar 107, which is fixed to the traverse frame, slides in bearings 108 of the frame 124 of the machine. During the operation of the machine a cylindrical rotatable roller 102, the so-called pressure roll, which is fixed to the traverse frame 101, rests against the yarn package. At one end the traverse bar 105 carries a small roller 109 at its lower side this roller being situated in the upper slot of the lever 120, a cross section view of which is shown in Figure 2a. This lever can swing about a vertical shaft at 112.

It is clear that when the lever 120 swings to and fro about its fulcrum 112, the traverse bar and the yarn guide will also move to and fro. In the first frame of the machine there are two guide bars 118, between which a small slide 128 is capable of sliding. As may be seen from Figure 2, this slide carries two small rollers 129, 204 one on its lower side and one on its upper side, these rollers being rotatable about vertical shafts. The upper roller 129 is situated in a lower slot of the lever 120 (which has an H-shaped cross section as shown in Figure 2a) and thus couples the slide to the lever. The lower roller 204 is situated in the slot 122 of a cylindrical body 119 which serves as traverse cam. This body is mounted on, and driven by, the shaft 123, which shaft is driven by the spindle 117 by means of the gears 127. When the spindle 117 and the shaft 123 are rotating, the body 119 will, by means of the slot 122, move the slide 128 to and fro between the guide bars 118. The slide will then drive the lever 120, which consequently 15 will swing about the shaft 112, causing the traverse bar 105 and the yarn guide 103 to move to and fro. The angle through which the lever 120 swings is constant. The stroke of the yarn guide is, however, determined by the position of the traverse frame. The stroke of 20 the traverse rod decreases as the traverse frame is moved farther from the spindle owing to the forces exerted by the yarn package building up. The rate of this decrease, and consequently the shape of the pine-apple cone, are determined by the position of the fulcrum 112. 25 30 35 40 45 50 55 60

The nearer the fulcrum 112 is situated to the spindle, the more acute will the conical surfaces 113 and 115 of the yarn package become. The ratio of the apex angles of these cones will, moreover, be influenced by a displacement of this fulcrum in a direction parallel to the spindle. If only one shape of yarn package is to be made, the fulcrum can be a fixed shaft. When, however, it is desirable for the machine to be capable of winding yarn packages of various forms, the position of the fulcrum 112 must be adjustable. The adjustability of the fulcrum 112 can be effected in various ways. As a rule, the changing of the shape of the yarn package and the displacing of the fulcrum will occur infrequently. Hence a simple method of adjustment is to be preferred. It would be possible, for instance, to provide the shaft 112 with a collar below the lever 120, and to mount it, by means of a nut, in an opening in a horizontal plate fixed to the frame of the machine, and shown in the figure. In this plate a fairly large number of openings would make the desired changes in the position of the fulcrum possible within the area in which these openings are situated, these openings being arranged according to a simple pattern. It is also possible to mount this fulcrum in the manner illustrated in Figure 1A. Herewith the fulcrum is mounted in a slot 31 in a horizontal plate 32, the slot being perpendicular to the spindle, and the plate itself being adjustable parallel to the spindle, for which purpose it is mounted on supports 35, 36 on the frame of the machine, by means of screws 33 in slots 34 of the said plate 32.

The axes of the roller bail 102 and of the spindle 117 are situated in one plane, this plane being parallel to the direction of displacement of the traverse frame 101. Consequently the roller bail will be in contact with the yarn package along a generatrix of this package independent of the position of the traverse frame, and will be capable of executing the same pressure on all parts of this package.

When the traverse frame moves in a horizontal direction, as is the case in the machine described, balancing measures are superfluous. If, for some reason, it is desirable that the direction of the displacement of the traverse frame should be other than horizontal, balancing can be effected in a simple way.

The forces exerted by the driving mechanism of the

traverse bar on the traverse frame in the direction of the displacement of this frame are considerably lower than in the known constructions. This is a result of the fact that the forces resulting from the friction in the slot of the traverse cam, and also the component perpendicular to the spindle of the force in this slot at right angles to it do not act on the traverse frame, but on the slide which runs between the guide rods 118. Undesirable forces on the traverse frame can only originate in the swinging lever 120, and as this swinging lever executes no motion perpendicular to the spindle, the friction of the small roller at the lower side of the traverse bar in the upper slot of this lever can cause no appreciable forces on the traverse frame which would drive this frame either in the direction of the yarn package or in the direction away from it. The angle between this lever and the traverse bar will, moreover, never be so acute as the angle between the traverse bar and the slot in the traverse cam, so that the forces exerted on the small roller of the traverse bar will have only a slight component in the direction of displacement of the traverse frame. To cause a further reduction in the influence of these slight forces it is to be recommended, that the traverse frame should be provided with a device of a well-known type permitting the traverse frame to move in the direction away from the spindle only. The form of such a device is immaterial to the invention, and any good friction pawl is suitable for this purpose.

The forces on the traverse frame can be reduced still further by modification of the driving mechanism of the traverse bar. This modification requires that either the one or the other of the two couplings of the type which permits a relative rotation and sliding motion of the parts coupled, i.e., the coupling between the said traverse bar 105 and the lever 120 or the coupling between the slide 128 and the lever 120, is replaced by a coupling of the type which permits only a relative rotation of the parts coupled, while the coupling between the lever 120 and the first frame 124 is replaced by a coupling which not only permits a relative rotation of these parts but at the same time permits a sliding motion of said lever along its fulcrum. This latter coupling may be embodied in the manner illustrated in Figure 1A in which the lever 120 can slide along the shaft 112 owing to the fact that the lever 120 is provided with a slot 37 which is capable of sliding along the pin 112. Another possible embodiment of this coupling is used in the machine shown in Figure 3, where the lever 120 slides in a small fork 348 which is rotatable about the pin 112 which projects from the bottom side of this fork.

The way in which the lever 120 is made to move to and fro is immaterial to the invention. The method of driving shown in Fig. 1 is convenient, since it permits the application of the standard form of the traverse cam. It would also, however, be possible to drive the swinging lever by means of a normal cam disc, or a disc provided with a slot of suitable shape, driven, for instance, by a vertical shaft. It would also be possible to combine the driving mechanisms of the lever 120 of a number of winding machines situated vertically above each other. A similar combined driving of machines situated side by side would also be possible. It is a disadvantage of such a combined driving of the traverse movement, that either all spindles of the machines coupled in this way must be stopped simultaneously, or a special coupling device must be mounted, permitting the disconnection of such a lever from the combined driving mechanism.

For certain applications it is desirable for the yarn package to possess a rounded shape. To form such a shape it is necessary that the decrease in the traverse length should be more than proportional to the displacement of the traverse frame. According to the invention this can be effected by means of a construction in which the traverse frame, whilst being shifted by the yarn

package, displaces the fulcrum 112 of the lever 120. In this case a construction is preferably applied in which the swinging lever slides along the fulcrum 112, because then smaller forces are exerted on the traverse frame by the device causing the displacement of the fulcrum. During the said displacement of the fulcrum 112 it must move in the direction of the spindle in accordance with the movement of the traverse frame away from the spindle. In Fig. 3 a form of such a construction is shown. Part 101 is the traverse frame with the traverse bar 105 driven by the swinging lever 120, this lever being capable of sliding in a fork 348 rotatable around a shaft 112. This shaft is carried by a bell crank lever 343 mounted on a shaft 344, which shaft is rotatable in the frame of the winding machine. The second arm of this bell crank lever carries a small roller 345, situated in a slot 346 of a plate 347 mounted on the traverse frame. If the slot has the shape shown in the figure the position of the fulcrum 112 will not at first change. The machine then winds the yarn package with normal conical ends. As soon, however, as the roller 345 enters the curved part of the slot 346, the lever 343 will move the fulcrum 112 in the direction of the spindle. The traverse length will then decrease at a rate which is higher than would be the case if it were influenced by the displacement of the traverse frame only. The shape of the yarn package can be influenced in the first place by the shape of the slot 346. Preferably, therefore, the plate 347 is interchangeable. Moreover the fulcrum 112 at the end of the bell crank lever can be made adjustable, for instance by providing this end with a number of openings in which the fulcrum 112 can be fixed, whilst in addition it would be possible to make the position of the shaft 344 carrying the bell crank lever adjustable in the frame of the machine. Fig. 3 shows only one method for automatically adjusting the fulcrum of the swinging lever 120. Other methods are, however, feasible. These methods need not result in a rounded shape of the yarn packages; many other shapes of yarn packages can be wound on machines with adjustable fulcrum of the swinging lever.

If it is desirable to form a yarn package with constant traverse length, the machine must be built in another way. It is then no longer possible to apply the swinging lever 120. Two constructions are suitable for this purpose. It would be possible (see Fig. 4) to replace the lever 120 by a bar provided with a slot in its lower side, which is rigidly fixed to the traverse bar and which cooperates by means of the said slot in its lower side with the roller or the like at the top side of the slide which moves to and fro between its guide bars. The angle between the slotted bar and the traverse bar is preferably adjustable, in order to permit the winding of various shapes of yarn packages. If this slotted bar is perpendicular to the direction of displacement of the traverse bar, then the two ends of the yarn package are conical surfaces, the generatrices of which are perpendicular to the surface of the tube on which the package is wound. If the said rod is perpendicular to the spindle, then the end surfaces of the yarn package are planes perpendicular to the spindle. If the slotted bar is adjusted in other positions, other shapes of yarn packages will be wound. Fig. 4 shows an example of such an embodiment. Part 101 is the traverse frame, 105 the traverse bar, and 120 the slotted bar, mounted on the traverse bar 105 and cooperating with the roller on the slide 128 which moves to and fro between the guide bars 118. The bar 120 is adjustably mounted to the traverse bar 105 by means of bolts and nuts (not shown) which permit the slotted bar to be adjusted in various positions. To prevent the load exerted on the traverse bar 105 by the bar 120 from causing the friction of the traverse bar to increase, the free end of the slotted bar 120 is provided with a fork 432, which slides over a supporting bar 433 mounted to

the traverse frame. Fig. 4, which, apart from the above, corresponds to Fig. 1, needs no further elucidation.

In another form of a winding machine for constant traverse length, shown in Fig. 5, the traverse bar 105 carries a small roller 109, just as in the machine shown in Fig. 1. This small roller runs in a U-shaped slot of a bar 120 which as to function corresponds to the bar 120 of Figure 4, this bar being able to slide to and fro along a guideway 118 in the frame of the machine said bar remaining during this sliding motion parallel to itself, the drive for this sliding motion being obtained, for instance, from a traverse cam 119. In this form also, the slotted bar 120 can have various positions relative to the spindle, and can thus cause the winding of the yarn package with constant traverse length of various forms. The bar 120 is prevented from turning over by means of a fork 532, which slides over a flat supporting rod in the frame 124. Due to the fact that the bar 120 cooperates with the roller 109 at the underside of the traverse bar, the traverse bar 105 will be moved to and fro with rotation of the traverse cam. The bar 120 is mounted on the slide 128 by means of a bolt and nut 533, and can be fixed by means of a second bolt 535 in a circular slot, in the position suitable for causing the desired shapes of the yarn package to be wound.

In the figures the winding machine is shown provided with a pressure roll. It is obvious that this device can be dispensed with if the properties of the yarn to be wound permits this, in which case the yarn guide is replaced by a kind of convex yarn-guide which is capable of sliding over the surface of the yarn package.

In the winding machine according to Fig. 1, provided with the swinging lever 120, it would in many cases appear unnecessary to take special measures for pressing the traverse frame against the yarn package. If it is desirable, however, for a pre-determined pressure to be exerted on the yarn package in every position of the traverse frame, then this can be effected in a simple way. In one of the forms of the winding machine a cord was fixed to the traverse frame, this cord passing over a rope pulley, a small weight being suspended from it. In this way a constant pressure on the yarn package is obtained. If it is desirable to obtain a pressure which is a pre-determined function of the position of the traverse frame, then it is possible to couple the traverse frame to a lever, on which a suitable force is exerted by means of a weight or a spring. Fig. 6A shows a first form of such a device. A lever 602 rotatable about the fulcrum 603, is coupled by means of a link 601 to the traverse frame 101. The lever 601 is coupled to a specially shaped sector 604, on which a steel strip rests, which is connected to a spring 605. A suitable shape of the sector 604 will cause the traverse frame, whatever its position may be, to exert the force required for this position on the yarn package. Instead of a spring 605, a weight suspended from the steel strip can also exert the force on the lever. In a second form shown in Fig. 6B a part of the traverse frame 101 sliding over a bar 655 is indicated by 656. It carries a small roller 654 on which forces are exerted by means of a lever 653, rotatable about a fulcrum 652. The lever is subjected to a torque by means of a spiral spring 651 mounted in a spring drum 650. The magnitude of the torque exerted by the spring can be adjusted by rotating the outside of the spring drum. A suitable shape of the lever 653 enables the force in the direction of the displacement of the traverse frame to be pre-determined in each position of this frame. It is obvious that other methods can also be applied, experience, however, has shown the methods described to be very effective.

Sometimes it is desirable to build a yarn package the traverse length of which is smallest on the inside and largest on the outside. Such yarn packages are specially suitable for unwinding from the inside of the package. The winding machine according to the invention is also suitable for the winding of such yarn packages.

A form of the winding machine according to the invention for this purpose is shown in Fig. 9. This machine corresponds in general to the machine shown in Fig. 1, with this difference, however, that the fulcrum 112 about which the lever 120 with H-shaped section swings is situated at the same side of the traverse frame 101 as the spindle. It is obvious that the traverse length increases as the traverse frame 101 moves away from the spindle 117, as the distance between the small roller 109 at the lower side of the traverse bar 105 and the fulcrum 112 about which the lever 120 swings also increases during this displacement of the traverse frame. The various forms of the machine according to the invention which are described above are also possible in the case of a machine according to Fig. 9. It is possible, for instance, to make the lever 120 slide along the fulcrum 112, this lever being rotatably supported on the slide which moves between the guideway 118. It is possible, moreover, to displace the fulcrum 112 automatically in accordance with the position of the traverse frame, in a similar way as has been described with reference to Fig. 3. Finally, it is possible to regulate the rotational speed of the spindle by means of a method which will be described with reference to Figs. 7 and 8.

25 The displacement of the fulcrum 112 depending on the displacement of the traverse frame 101, in the manner described with reference to Fig. 3, can, in the case of certain forms of the yarn package, be effected in a simple way by mounting this fulcrum on the traverse frame 101. 30 Fig. 10 shows such a machine. If it is desirable to wind a yarn package the traverse length of which is smallest on the inside, then the fulcrum must be situated on the other side of the traverse frame, i.e. the side where the spindle is situated.

35 In most cases in modern winding machines the limit of the rotational velocity of the spindle of a precision winding machine is not determined by the properties of the yarn, but by the traverse mechanism. Our new traverse mechanism permits higher rotational speeds, so that the use of our new machine, entails a higher probability of the yarn speed becoming excessive, when the yarn package reaches its greatest diameter. Especially in the case of the yarn being wound from reels, in which case the yarn speed must, as a rule, be rather low, it may occur that the yarn speed sets a limit to the rotational speed of the spindle. In this case winding at a constant yarn speed is preferable to winding at a constant speed of the spindle, or at any rate it is desirable that, during the winding of the complete yarn package, the speed should be kept nearer to the maximum than in the case of constant spindle velocity yarn speed. The application of friction drives with continuously variable transmission ratio is a known solution for this purpose, the transmission ratio being adjusted by the traverse frame whilst

40 changing its position. In the machine according to the invention such variable spindle velocity can be obtained in a very simple and effective way. A first form of a machine with variable spindle velocity according to the invention is shown in Fig. 7. In this machine the spindle 117 carries at one end the disc 171, which is capable of sliding along the spindle, but which, owing to the presence of a key, can not rotate with respect to this spindle, whilst a spring 170 presses the disc in the direction of the shaft 175. Between the shaft 175 and the disc 171 there are two balls 173 and 174, enclosed in a ball carriage 172,

45 which completely determines the position of these balls, but in which these balls are freely and universally rotatable. In the ball carriage shown, every ball is supported between two cup-shaped members 176 in which these balls are supported by means of a number of smaller bearing balls, so that the larger balls are capable of rotating with very little friction around an axis which is parallel to the shaft 175, whilst transferring motion between shaft and disc, as well as around an axis which is perpendicular to the shaft 175, but is parallel to the disc 171, whilst

the ball carriage is shifted for the purpose of changing the transmission ratio. The ball carriage 172 is coupled by means of an arm 177 to the traverse frame 101. The spring 170 presses disc, ball and shaft together in such a way that, when the shaft rotates, the motion of this shaft is transferred by means of the two balls to the disc and the spindle of the winding machine. The shaft is driven at constant velocity by the driving motor of the winding machine. It is obvious that the transmission ratio of the transmission gear varies when the position of the traverse frame changes and that this transmission ratio decreases, causing the spindle to rotate more slowly in accordance with the increase of the diameter of the yarn package. If the yarn speed is restricted to a low value, it is then, as a rule, admissible to arrange the relative position of ball carriage 112 and traverse frame 101 in such a way that the yarn speed is kept completely constant. In many cases, however, the traverse mechanism would then obtain excessive rotational velocities when the diameters of the yarn package are still small. In such cases the extent of the adaptation is limited, and only such a change in the transmission ratio is possible as would cause the yarn speed to be equal to the maximum admissible yarn speed when the diameter of the yarn package is largest, and, when the diameter of the yarn package is smallest, would cause a rotational velocity of the spindle which does not surpass the maximum rotational velocity permitted by the traverse mechanism. In this case the point of contact between ball and disc must be situated at a distance from the centre of the disc which is larger than that separating the pressure roll from the axis of the spindle. The transmission gear provided with balls has the important advantage that the balls are capable of free rotation in opposite directions, rolling on disc and shaft, when the ball carriage is displaced for the purpose of changing the transmission ratio. Consequently the traverse frame is not subjected to noticeable forces exerted by the ball carriage. It would, however, also be possible to apply a small wheel instead of the two balls, this wheel being shiftable along the shaft 175, but not capable of rotating with respect to this shaft, for instance because of being coupled to the shaft by means of a key. The spring 170 then presses the disc 171 against the wheel, and the wheel is shifted along the shaft by means of an arm mounted on the traverse frame in order to change the transmission ratio of the transmission gear.

Finally a form of the machine according to the invention will be described in which the traverse frame is rigidly mounted, the spindle executing a translational motion away from the traverse frame as the diameter of the yarn package grows. Generally this form will be less attractive than the form in which the traverse frame executes the translational motion, because the driving of a spindle which can be shifted away from the yarn package will present difficulties, whilst, moreover, the weight of the parts which must be shifted when the diameter of the yarn package increases, will be larger in the case of the spindle being shifted. In the design of the driving mechanism of such a spindle care must be taken that no forces possessing components in the direction of the translational motion of the spindle are exerted on the spindle by this driving mechanism, as these components would influence the pressure on the yarn package. As a rule it would not be feasible to prevent the originating of such forces if either the driving of the spindle or the coupling between the shaft of the traverse cam and the spindle were effected by means of a system of three or more spur gears, mounted on two coupled arms, capable of swinging around the two shafts to be coupled. The driving of a spindle capable of translational motion must, for the purpose of preventing the arising of such forces, be effected by means of gears coupling mutually perpendicular shafts, the gear mounted on the driving shaft being capable of shifting

along this shaft, but not capable of rotating with respect to this shaft. The mounting of the spindle in such a way that it becomes capable of effecting a translational movement permits, however, the application of a simple method for adapting the rotational speed of the spindle to the diameter of the yarn package. A winding machine in which such an adaption is effected is shown in Fig. 8. In this machine 117 is the spindle capable of rotating in bearings in a first frame 124. This frame is carried by two cylindrical bars 107 and 111 which are fixedly supported in the second frame 828 of the machine. The first frame 124 is capable of sliding along the bars 107 and 111 by means of bearings 108 and 110, the said bars also carrying the traverse frame 101, which is rigidly mounted to these bars. The driving of the spindle is effected by means of a disc 171, which is capable of sliding longitudinally on the spindle, but which is not capable of rotating with respect to this spindle, it being coupled to the spindle by means of a key. Spring 170 presses the disc in the direction of the driving shaft 175. Between this disc and this shaft there are two balls 173 and 174 mounted so as to be universally rotatable in a ball carriage 172. The balls are supported in this carriage by means of two cup shaped devices, in which they are supported by means of small balls so as to be universally rotatable. The spring 170 presses disc, balls and shaft together in such a way that a transmission of motion between the shaft and the spindle becomes possible. The ball carriage 172 is supported on the second frame of the winding machine, so that the transmission ratio of the transmission gear consisting of the disc, the balls and the shaft varies when the first frame 124 is shifted along the bars 107 and 111 owing to the forces exerted on the spindle as the yarn package builds up. In the first frame 124 a swinging lever 120 is mounted in a similar way as in the machine according to Fig. 1. The lever 120 drives the traverse bar 105 and is itself driven by a slide 128 which is moved to and fro along two guide rods 118 by means of a traverse cam 119. The traverse cam is mounted on a shaft 123, which is rotatable in the first frame 124, and is driven by the spindle by means of the spur gears 127. In the same way as in the machine according to Fig. 1, the lever 120 will be caused to execute a swinging motion when the spindle is rotating, causing the traverse bar 105 and the yarn guide 103 to move to and fro. During the winding the pressure roll 102 rests against the surface of the yarn package, which consequently will cause the spindle to move away from the traverse frame when the diameter of the yarn package grows. The roller at the under side of the traverse bar 105 will then move nearer to the fulcrum 112 of the swinging lever 120, causing the traverse length to decrease. Moreover, the point of contact between the ball 173 and the disc 171 will move away from the centre of the disc, causing the rotational speed of the spindle to be decreased. In this way it is possible to cause the yarn speed to be constant, but if, at a constant yarn speed equal to the maximum value the rotational speed of the spindle were to become too high for the traverse mechanism when the diameter of the yarn package is small, then the construction according to the invention still permits the yarn speed to approximate more closely to a constant yarn speed than would be possible if the spindle were rotating at a constant speed. The various forms of the machine according to the invention described above are also possible in the case of the machine according to Fig. 8. An automatic adjustment of the fulcrum 112, the winding of the yarn package the traverse length of which is smallest at the inside and also the winding of a yarn package with constant traverse length would be possible by applying the means described above. The machines according to the invention have been described in a form suitable for winding conical yarn packages, but it is obvious that these ma-

chines can be applied equally well for the winding of cylindrical packages. For this purpose the traverse frame must be mounted in such a way that the traverse bar moves along a path which is parallel to the spindle, and, a pressure roll, if such a device is present, is rotatable around an axis which is parallel to the said spindle, this being feasible in all constructions described. In all forms of the invention described it would, moreover, be possible to mount the traverse frame in such a way that its direction is adjustable so as to make the machine suitable for winding cones of various shapes as well as cylindrical packages, for the coupling between the traverse bar and the device directly driving it is independent of the direction of the traverse frame. Furthermore, it would be possible to mount the traverse frame in such a way that the direction of the motion of the traverse bar and the direction of the axis of the pressure roll, if such a device is present, are parallel to the shaft around which the traverse cam rotates, also in the case of a conical yarn being wound. The spindle must in this case be mounted in such a way that it is not parallel to the shaft of the traverse cam.

In a winding machine according to the invention for winding conical yarn packages and provided with a pressure roll, the best results are obtained when the axis of the spindle and the axis of rotation of the pressure roll are situated in the same plane, this plane being parallel to the direction of the relative translational motion of spindle and traverse frame, for in this case the pressure roll will, in any relative position of spindle and traverse frame, rest against the yarn package along the full length of a generatrix of its surface. If such a machine does not possess a pressure roll, the path described by the point of contact between the yarn guide and the yarn package should preferably be situated in a plane through the axis of the spindle and parallel to the direction of the relative translational motion of spindle and traverse frame, for in this case the said path will coincide with a generatrix of the surface of the yarn package in any relative position of spindle and traverse frame. If only cylindrical yarn packages are to be wound it is not necessary for the said axis of the pressure roll and the path of the said point of contact to be situated in the plane described, and in order to ensure that there will be a contact along a generatrix of the surface of the yarn package, or that the said path will coincide with such a generatrix, it is sufficient for the said axis of the pressure roll or the said path of the point of contact to be parallel to the axis of the spindle.

In the above specification various forms according to the invention are described, each of these forms being capable of winding a special shape of yarn package. It is feasible according to the invention to apply the same machine for winding all forms of yarn packages simply by exchanging certain parts. The slide, driven by the traverse cam, can be used to drive a swinging lever rotatable around a shaft which is situated on the same side of the traverse frame as the spindle, as well as a lever capable of swinging about a shaft which is situated on the opposite side of the traverse frame. In the case of driving by means of the slide, moreover, it is immaterial whether the shaft, around which the lever swings, is supported by the first frame, or by the second traverse frame. If the swinging lever is dismantled, and a suitable bar is mounted on the traverse bar, the same slide can cause a traverse motion of the traverse bar, with constant traverse length. For this purpose the slide could also be made to carry a bar which forms a guide cooperating with the roller at the underside of the traverse bar for instance, in this way also bringing about a traverse motion with constant traverse length. A supporting lever for the fulcrum of the swinging lever, as shown in Fig. 3, for the purpose of winding cones of various shapes, can be mounted on a machine which normally operates with a fixed fulcrum for the said swinging lever. All these features are possible

in the same winding machine, the measures necessary for such allround application being little more than the provision of some extra bolt holes.

A method for driving the traverse bar in such a way that the forces driving this bar are exerted centrally on it, thus reducing the friction of the traverse bar in the traverse frame, is shown in Fig. 11. In this figure 101 is a section of the traverse frame, 105 a section of one end of the traverse bar, this end being provided with a cylindrical opening in which a cylindrical pin 109 can rotate. A cylindrical bar 179 is capable of sliding through an opening in this pin and passes through slots in the end of the traverse bar as well as in the traverse frame. The cylindrical bar is carried by the U-shaped swinging lever 120 which is rotatably mounted on to the slide 128. This slide is capable of moving along the guides 118. The lower end of the slide 128 carries a small roller 204 which is situated in the slot of the traverse cam (not shown) driving the slide. The bar 179 is capable of sliding in a block 180 which can swing about the shaft 112. The figure needs no further elucidation. It would also be possible for the bar 179 to be only rotatable around the shaft 112, the U-shaped member swinging lever 120 in this case possessing some kind of guide by means of which it cooperates with a coupling member on the slide 128.

Recapitulating, the following methods for driving the traverse bar in a machine according to the invention can be stated. Although other driving methods are feasible, the following methods are preferable for driving the traverse bar of a yarn winder for winding pineapple cones:

I. A lever is caused to swing about a shaft supported either on the first frame carrying the spindle or on the second traverse frame. It is coupled to the traverse bar by means of a guide and a coupling element capable of sliding along the guide.

The lever also carries a guide which cooperates in a similar way with a coupling element on a slide moving to and fro along suitable guide rods, and cannot slide with respect to the shaft around which it is caused to swing.

II. The lever can slide with respect to the shaft around which it is caused to swing and is coupled to the said slide by means of a coupling permitting mutual rotation only, while it is coupled to the traverse bar by means of a guide and a coupling element which together constitutes a coupling permitting relative rotation and sliding motion of the part coupled.

III. The lever is coupled to the traverse bar by means of a joint permitting mutual rotation only, the arm being capable of rotating around as well as of shifting along a shaft which is supported either by the traverse frame or by the frame carrying the spindle.

The lever also carries a guide which cooperates with the coupling element on a slide moving to and fro along suitable guide rods. This latter coupling permitting a relative rotation and sliding motion of the parts coupled.

In the above specification the machine has been described as a machine for winding textile yarns. It is obvious that it is capable of winding filaments, threads or wires of any type provided that the diameter is not too large.

What I claim is:

1. A winding machine for producing wound filament packages, comprising, in combination, a rotating spindle carrying and driving a winding package, a rotating camshaft geared to said spindle and driven therewith, a reciprocating element driven by said rotating camshaft; a first frame for mounting said spindle with said camshaft and said reciprocating element, a thread guide, a second frame having a primary guide means carrying and guiding said thread guide for movement parallel to the face of the package, a secondary guide means mounted in said first frame and carrying said second frame and accommodating relative rectilinear translational motion of said first frame and said second frame as said package builds up, and a movable coupling having slidable guide means operatively

connecting said reciprocating element in said first frame with said thread guide in said second frame to impart a reciprocating motion to said thread guide in response to reciprocating movement of said reciprocating element.

2. A winding machine for producing wound filament packages comprising, in combination, a rotating spindle carrying and driving a winding package, a rotating cam-shaft geared to said spindle and driven therewith, a slide, a guideway confining said slide to reciprocating movement along a fixed path during rotation of said cam-shaft, a first frame supporting said spindle, said cam-shaft, said guideway, and said reciprocating slide, a second frame having a trackway in parallel to the face of the package, a thread guide, a traverse bar supporting said thread guide, said traverse bar being slidably supported in said trackway and constituting a primary guide means therewith, a second guide means mounted in said first frame carrying said second frame and accommodating a relative rectilinear translational motion of said first frame and said second frame as the package builds up, a second bar mounted upon said reciprocating slide having means defining another path lying in a plane extending parallel to the rectilinear translational motion of said first and second frames and parallel to the center line of said spindle, a coupling element carried by said traverse bar for movement along said fixed path, said second bar and said coupling element being connected between said reciprocating slide in said first frame and said traverse bar carrying said thread guide in said second frame and imparting a reciprocating motion thereto.

3. A winding machine for producing wound filament packages comprising, in combination, a rotating spindle carrying and driving a winding package, a rotating cam-shaft geared to said spindle and driven therewith, a slide, a guideway confining said slide to reciprocating movement along a fixed path during rotation of said cam-shaft, a first frame supporting said spindle, said cam-shaft, said guideway, and said reciprocating slide, a second frame having a trackway parallel to the face of the package, a traverse bar slidably supported in said trackway, a thread guide supported in said traverse bar, secondary guide means mounted in said first frame and carrying said second frame, said secondary guide means accommodating relative rectilinear translational motion of said first frame and said second frame as the package builds up, a second bar mounted upon said traverse bar having means defining another path lying in a plane which extends parallel to the rectilinear translational motion of said first and second frames and parallel to the center line of said spindle, a coupling element carried by said reciprocating slide for movement along said fixed path, said second bar and said coupling element connecting said reciprocating slide in said first frame and said traverse bar carrying said thread guide in said second frame and imparting a reciprocating motion thereto.

4. A winding machine for producing wound filament packages comprising, in combination, a rotating spindle carrying and driving a winding package, a rotating cam-shaft geared to said spindle and driven therewith, a slide, a guideway confining said slide to reciprocating movement along a first path during rotation of said cam-shaft, a first frame supporting said spindle, said cam-shaft, said guideway, and said reciprocating slide, a second frame having a trackway parallel to the face of the package, a thread guide, a traverse bar slidably supported within said trackway and carrying said thread guide, said traverse bar providing a primary guide means for said thread guide, a secondary guide means mounted in said first frame and carrying said second frame, said secondary guide means accommodating relative rectilinear translational motion of said first frame and said second frame, a lever supported for oscillation within a plane extending parallel to the plane of said relative

rectilinear translational motion of said first and second frames and parallel to the reciprocating motion of said slide, first, second, and third coupling means coupling said lever each to one of said frames, said slide, and said traverse bar, respectively, each one of said three coupling means accommodating relative rotation of said lever and the respective part coupled thereto, two of said three coupling means accommodating relative sliding motion of the respective coupled parts, and a driving connection between said reciprocating slide in said first frame and said traverse bar carrying said thread guide in said second frame imparting a reciprocating motion to said thread guide.

5. A winding machine for producing wound filament packages comprising, in combination, a rotating spindle carrying and driving a winding package, a rotating cam-shaft geared to said spindle and driven therewith, a slide, a guideway confining said slide to reciprocating movement along a fixed path during rotation of said cam-shaft, a first frame supporting said spindle, said cam-shaft, said guideway, and said reciprocating slide, a second frame having a trackway parallel with the face of the package, a thread guide, a traverse bar slidably supported within said trackway and supporting said thread guide, said traverse bar constituting a primary guide means for said thread guide, secondary guide means mounted in said first frame and carrying said second frame, said secondary guide means accommodating relative rectilinear translational motion between said first and second frames, a coupling system comprising a lever supported for oscillation within a plane extending parallel to a plane defined by said rectilinear translational motion of said first and second frames and parallel to the center line of said spindle, first coupling means coupling said lever with said first frame for relative rotation between said lever and said first frame, second coupling means coupling said lever with said slide for relative rotation and sliding motion of said lever and said slide, and third coupling means coupling said lever with said traverse bar for relative rotation and sliding motion of said lever and said traverse bar, whereby said coupling system drivingly connects said reciprocating slide in said first frame and said traverse bar carrying said thread guide in said second frame for imparting a reciprocating motion to said thread guide.

6. A winding machine for producing filament packages comprising, in combination, a rotating spindle carrying and driving a winding package, a rotating cam-shaft geared to said spindle and driven therewith, a slide, a guideway confining said slide to reciprocating movement along a fixed path during rotation of said cam-shaft, a first frame supporting said spindle, said cam-shaft, said guideway, and said reciprocating slide, a second frame having a trackway parallel to the face of the package, a thread guide, a traverse bar slidably supported within said trackway, said traverse bar supporting said thread guide and constituting a primary guide means therefor, a secondary guide means mounted in said first frame and carrying said second frame, said secondary guide means accommodating relative rectilinear translational motion of said first and second frames, a coupling system comprising a lever mounted for oscillation in a plane extending parallel to the plane defined by the rectilinear translational motion of said first and second frames, and parallel to the center line of said spindle, first coupling means coupling said lever with said second frame for relative rotation of said lever and said first frame, second coupling means coupling said lever with said slide for relative rotation and relative sliding motion of said lever and said slide, third coupling means coupling said lever with said traverse bar for relative rotation and a relative sliding motion of said lever and said traverse bar, said coupling system drivingly connecting said reciprocating slide in said first frame and said traverse bar and

carrying said thread guide in said second frame to impart a reciprocating motion to said thread guide.

7. A winding machine producing filament packages comprising, in combination, a rotating spindle carrying and driving a winding package, a rotating camshaft geared to said spindle and driven therewith, a slide, a guideway confining said slide to reciprocating movement along a fixed path during rotation of said camshaft, a first frame supporting said spindle, said camshaft, said guideway, and said reciprocating slide, a second frame having a trackway parallel to the face of the package, a thread guide, a traverse bar slidably supported within said trackway, said traverse bar supporting said thread guide and constituting primary guide means therefor, secondary guide means mounted in said first frame and carrying said second frame, said secondary guide means accommodating relative rectilinear translational motion of said first frame and said second frame, a coupling system comprising a lever mounted for oscillation within a plane extending parallel to a plane defined by the rectilinear translational motion of said first and second frames and parallel to the center line of said spindle, first coupling means coupling said lever with said first frame and accommodating relative rotation and sliding motion of said lever and said first frame, second coupling means coupling said lever with said slide for relative rotation and sliding motion of said lever and said slide, third coupling means coupling said lever with said traverse bar for relative rotation of said lever and said traverse bar, and said coupling system providing a driving connection between said reciprocating slide in said first frame and said traverse bar carrying said thread guide in said second frame and imparting a reciprocating motion to said thread guide in response to rotation of said camshaft.

8. A winding machine for producing filament packages comprising, in combination, a rotating spindle carrying and driving a winding package, a rotating camshaft geared to said spindle and driven therewith, a slide, a guideway confining said slide to reciprocating movement along a fixed path during rotation of said camshaft, a first frame supporting said spindle, said camshaft, said guideway, and said reciprocating slide, a second frame having a trackway parallel to the face of the package, a thread guide, a traverse bar slidably supported within said trackway, said traverse bar supporting said thread guide, and constituting a primary guide means therefor, secondary guide means mounted in said first frame and carrying said second frame, said secondary guide means accommodating relative rectilinear translational motion between said first frame and said second frame as the package builds up, a coupling system comprising a lever mounted for oscillation within a plane extending parallel to the relative rectilinear translational motion of said first and second frames and parallel to the center line of said spindle, first coupling means coupling said lever with said second frame and accommodating relative rotation and sliding motion therebetween, second coupling means coupling said lever with said slide for relative rotation and sliding motion therebetween, and third coupling means coupling said lever and said traverse bar for relative rotation of said slide and said traverse bar, whereby said coupling system drivingly connects said reciprocating slide in said first frame and said traverse bar carrying said thread guide in said second frame to impart a reciprocating motion to said thread guide in response to rotation of said camshaft.

9. A winding machine producing filament packages comprising, in combination, a rotating spindle carrying and driving a winding package, a rotating camshaft geared to said spindle and driven therewith, a slide, a guideway confining said slide to reciprocating movement along a fixed path during rotation of said camshaft, a first frame supporting said spindle, said camshaft, said guideway, and said reciprocating slide, a second frame

having a trackway parallel to the face of the package, a thread guide, a traverse bar slidably supported within said trackway and supporting said thread guide, said traverse bar constituting a primary guide means for said thread guide, secondary guide means mounted in said first frame, and carrying said second frame, said secondary guide means accommodating relative rectilinear translational motion of said first and second frames, a coupling system comprising a lever mounted for oscillation within a plane extending parallel to a plane defined by the relative rectilinear translational motion of said first and second frames and parallel to the center line of said spindle, first coupling means coupling said lever with said first frame and accommodating relative rotation and sliding motion therebetween, second coupling means coupling said lever with said slide for relative rotation between said lever and said slide, third coupling means coupling said lever with said traverse bar and accommodating rotation and sliding motion therebetween, said coupling system drivingly connecting said reciprocating slide in said first frame and said traverse bar carrying said thread guide in said second frame to impart a reciprocating motion to said thread guide in response to rotation of said camshaft.

10. A winding machine for producing filament packages comprising, in combination, a rotating spindle carrying and driving a winding package, a rotating camshaft geared to said spindle and driven therewith, a slide, a guideway confining said slide to reciprocating movement along a fixed path during rotation of said camshaft, a first frame supporting said spindle, said camshaft, said guideway, and said reciprocating slide, a second frame having a trackway parallel to the face of the package, a thread guide, a traverse bar slidably supporting said thread guide within said trackway, said traverse bar supporting said thread guide, and constituting a primary guide means therefor, secondary guide means mounted in said first frame and carrying said second frame, said secondary guide means accommodating relative rectilinear translational motion of said first frame and said second frame, a coupling system comprising a lever mounted for oscillation in a plane extending parallel to a plane defined by relative rectilinear translational motion of said first and second frames and parallel to the center line of said spindle, first coupling means coupling said lever with said second frame accommodating relative rotation and sliding motion between said lever and said second frame, second coupling means coupling said lever with said slide for accommodating relative rotation of said lever and said slide, third coupling means coupling said lever and said traverse bar accommodating relative rotation and sliding motion of said lever and said traverse bar, and said coupling system drivingly connecting said reciprocating slide in said first frame and said traverse bar carrying said thread guide in said second frame to impart a reciprocating motion to said thread guide in response to rotation of said camshaft.

11. A winding machine for producing filament packages comprising, in combination, a rotating spindle carrying and driving a winding package, a rotating camshaft, said camshaft being geared to said spindle and driven therewith, a slide, a guideway confining said slide to reciprocating movement along a fixed path during rotation of said camshaft, a first frame supporting said spindle, said camshaft, said guideway, and said reciprocating slide, a second frame having a trackway parallel to the face of the package, a thread guide, a traverse bar carrying said thread guide, said traverse bar being slidably supported within said trackway and constituting a primary guide means for said thread guide, secondary guide means mounted in said first frame and carrying said second frame accommodating relative rectilinear translational motion of said first frame and second frame, a coupling system comprising a lever mounted for oscillation within a plane extending parallel to a plane defined by the relative

tive rectilinear translational motion of said first and second frames and parallel to the center line of said spindle, first coupling means coupling said lever to a part mounted for movement upon one of said frames, means automatically displacing said part with respect to said frame in response to relative movement between said first and second frames, second coupling means coupling said lever to said slide, third coupling means coupling said lever to said traverse bar, each of said coupling means accommodating relative rotation of said lever and the respective part coupled thereto, two of said coupling means accommodating relative sliding motion of the respective coupled parts, and said coupling system providing a driving connection between said reciprocating slide in said first frame

5

10

and said traverse bar carrying said third guide in said second frame to impart a reciprocating motion to said thread guide in response to rotation of said camshaft.
